CLAIM

The ornamental design for an angle head, as shown and described.

DESCRIPTION

FIG. 1 is a front, top, left side perspective view of an angle head showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof;

FIG. 7 is a rear elevational view thereof; and,

FIG. 8 is a rear, top, left side perspective view thereof.

The broken lines showings in the drawings are for illustrative purposes only and form no part of the claimed design.
